(57) **CLAIM**

The ornamental design for a post with crown having two points of adjustment, as shown, and described.

DESCRIPTION

FIG. 1 is a perspective view of the post with crown having two points of adjustment;

FIG. 2 is a front view of the post with crown having two points of adjustment;

FIG. 3 is a back view of the post with crown having two points of adjustment;

FIG. 4 is a left side view of the post with crown having two points of adjustment;

FIG. 5 is a right side view of the post with crown having two points of adjustment;

FIG. 6 is a top view of the post with crown having two points of adjustment;

FIG. 7 is a bottom view of the post with crown having two points of adjustment;

FIG. 8 is a perspective view of an alternative embodiment of the post with crown having two points of adjustment;

FIG. 9 is a front view of an alternative embodiment of the post with crown having two points of adjustment;

FIG. 10 is a back view of an alternative embodiment of the post with crown having two points of adjustment;

FIG. 11 is a left side view of an alternative embodiment of the post with crown having two points of adjustment;

FIG. 12 is a right side view of an alternative embodiment of the post with crown having two points of adjustment;

FIG. 13 is a top view of an alternative embodiment of the post with crown having two points of adjustment; and,

FIG. 14 is a bottom view of an alternative embodiment of the post with crown having two points of adjustment.
